BABY BOTTLE

Phillip V. Kantz, Skokie, Ill., assignor to The Kendall Company, Walpole, Mass.

Filed June 28, 1972, Ser. No. 266,951

Term of patent 14 years

Int. Cl. D24—04; D9—01

U.S. Cl. D83—8 A

FIG. 1

FIG. 2

FIG. 3

FIG. 4

FIG. 5

FIG. 1 is a top plan view of a baby bottle embodying my new design;

FIG. 2 is a bottom plan view of the baby bottle of FIG. 1;

FIG. 3 is a rear elevational view of the baby bottle of FIG. 1;

FIG. 4 is a front elevational view of the baby bottle of FIG. 1; and

FIG. 5 is a side elevational view of the baby bottle of FIG. 1.

I claim:

The ornamental design for a baby bottle, substantially as shown and described.
